2

The invention relates to an apparatus for the briquetting of granular or powdery material. For briquetting of materials like coal-fines or powdery lignite normally stampers, so-called Exter-presses, of various design or roller presses with two rolls have been used. For the briquetting of very fine lignite a roller-ring press has been developed, by which briquettes of a very high density and weather-resisting quality can be produced. However, this kind of a press is exceedingly expensive as its large rollering is made of high-grade steel, which can be manufactured and repaired only on special lathes not available in briquetting factories. Such presses have, therefore, been employed only to a limited extent.

A device based on this same principle has been proposed before, but in this case the difficulty of controlling the bending stresses on the shaft could be overcome only by using two disks rotating eccentrically in opposite directions, and the diameter of the stationary ring could not be reduced at all. In order to reduce the pressure load on the shaft and to eliminate bending stresses on the crank the vertical component of the operating pressure is according to the invention transmitted directly to a plain horizontal bearing mounted on the frame. In this way the power required for operating the press is also reduced considerably, because the relative movement of this bearing of the pressure disk is very small.

To insure a uniform supply of the material to the slot a hopper is arranged above the ring and the main shaft is extended into the hopper and one or several bars are fitted to this upper part of the shaft which thoroughly mix the material in the hopper and if suitably designed also serve to shove the material into the slot in uniform quantities. The mixing effect, which is essential in the case of briquetting coal with a binder can be increased if the inner wall of the hopper is also fitted with bars or arms.

When a dry material is briquetted the slot is preferably closed at the side by a tongue-like bar fixed to the main shaft and sliding on the disk during its rotation. In the rolling-ring system of briquetting the briquettes are formed in an endless string, which can be subdivided by teeth provided on the periphery of the disk and then broken into individual briquettes. For this purpose a knife or scraper is fixed on the bar or directly on the main shaft. The knife scrapes off the string from the ring and breaks it up into briquettes, which drop to the bottom of the frame. For briquetting a material, that softens or melts at higher temperatures, superheated steam or hot gases may be introduced into the hopper.

In order to avoid overloading of the shaft in case too much material is fed into the slot of the press the axial bearing of the disk is connected with the eccentric through intermediary springs or a hydraulic device in a manner known per se. If the latter is used the pressure can be controlled perfectly and a uniform quality of the briquettes is maintained even if the quantity of material introduced fluctuates considerably.

An apparatus according to the invention is shown diagrammatically and by way of example in the drawing in which:

Fig. 1 is a vertical section through the press.

Fig. 2 is a section along line I—I, and

Fig. 3 is a section along line II—II in Fig. 1.

1 The invention relates to an apparatus for the briquetting of granular or powdery material.

For briquetting of materials like coal-fines or powdery lignite normally stampers, so-called Exter-presses, of various design or roller presses with two rolls have been used. For the briquetting of very fine lignite a roller-ring press has been developed, by which briquettes of a very high density and weather-resisting quality can be produced. However, this kind of a press is exceedingly expensive as its large rollering is made of high-grade steel, which can be manufactured and repaired only on special lathes not available in briquetting factories. Such presses have, therefore, been employed only to a limited extent.

This invention relates to an apparatus without the great disadvantages of the roller-ring press but without giving-up the favourable effect of the roller-ring and disk principle. According to the invention it has been possible to replace the large rotating vertical ring of 12 feet diameter of the roller-ring press by a stationary horizontal ring of smaller diameter e. g. of only 4 feet diameter. Inside of this horizontal ring a vertical shaft rotates, which carries a horizontal disk and by means of an eccentric on the shaft this disk rolls along the inside of the ring forming a slot between the ring and the disk. In this slot granulated material is fed from above and the material is compressed to an endless string of briquettes, as this slot is continuously widened and narrowed by the eccentrically rotating disk. The briquettes, formed in the slot drop to the bottom of the apparatus after having been broken from the endless string by a suitable device.

The small stationary ring used in the invention does not require any bearings and in spite of its small dimensions the leading angle of the briquetting slot is even more favourable than that of the known roller-ring press, the inside-diameter of the ring and the outside diameter of the disk being nearly the same in the apparatus of the invention.

The ring is fastened to a cast steel frame. In this frame a vertical shaft rotates coaxially with the ring. This shaft carries on its upper end an eccentric crank shaft and on its lower end a spur gear by which it is rotated in the usual way. The horizontal disk is moved by the eccentric crank shaft in such a way that when the main shaft is rotated the disk rolls along the inside of the stationary ring due to the friction of the material fed into the slot. In order to hold the material in the slot the periphery of the ring is stepped upward and that of the disk downward.

Fig. 4 is a horizontal section showing the disc mounted on an eccentric containing a hydraulic device.

In the frame 1 made of steel or cast-steel the vertical shaft 3 is mounted in bearings. The frame is closed on top by a ring 2. Below the ring 2 the disk 4 is mounted on the eccentric 21, surrounding part 5 of the shaft 3 by means of the bearing 6. In vertical direction the disk 4 rests directly on the bottom of the frame 1 by means of the thrust bearing 7. The shaft is rotated by a spur gear 8 in the usual way. Between part 5 of the shaft and the eccentric 21 there are arranged on one side of part 5 several flat or elliptic springs 9 so that the pressure disk is resiliently supported and can yield somewhat when excessively high pressures occur on the narrowest part 22 of the press channel. Above the disk 4 a hood 10 is fastened to the crank by means of a key 26. This hood carries an arm 11, which extends into the hopper 12 placed above the ring. The walls of the hopper 12 are also fitted with arms or bars 13. Fixed to the hood 10 by means of arms 14 and rotatable therewith is the tongue 15, which during rotation closes or shields a part of the slot 27 between the ring and the disk to the outside in a horizontal direction. Attached to the tongue is a scraper 16, which loosens the briquettes from the ring and drops them into the annular space 20 which is formed by frame 1 and a cylindrical projection 23 provided on this frame. Within this space a shovel 17, fixed to the tongue 15, moves the briquettes to the chute 18. Pipe 19 is connected to the hopper 12 and serves for the introduction of hot gases into the material.

When the shaft 3 is rotated, the disk 4, due to the friction of the material filled into the slot 27 between the ring and the disk, rolls along the inside of the ring and the slot is opened and closed periodically during the eccentric rotation of the disk. Depending on the eccentricity of the crank and the width of the slot a pressure up to 2500 atmospheres is exerted on the material. The material, preferably mixed before in the hopper by the movement of the mixing arms 11 and 13, flows into the open section of the slot by gravity, which opens periodically on the side opposite to the crank throw. The disk by its eccentric rotation closes the slot 27 and slowly narrows it, pressing the material to an endless string of briquettes. Behind the narrowest part of the slot the pressure is released automatically. The string remains inside the ring 2 until removed by the scraper 16. The string of briquettes 30, which preferably is subdivided by the effect of ribs 29 provided on the disk, is broken into individual briquettes by the scraper 16 according to the grooves produced by those ribs. The briquettes fall into the space 20 and are transported to the discharging-chute 18 by the rotating shovel 17.

A thorough mixing of the material, which is important for briquetting with a binder, is procured by the arms 11 and 13. These arms can also be used for a uniform feeding of the slot, preferably by inclining the arms toward the slot.

When coal is briquetted with a binder like pitch, superheated steam may be introduced into the hopper. Due to the high pressure, which can be exerted with an apparatus according to the invention, this apparatus can also be used for briquetting material that softens, like coking-coal, without any binder. Also mixtures of coke-breeze or anthracite and coking-coal can be briquetted at the softening temperatures of the coking-coal. In this case hot gases are introduced

e. g. by the line 19 into the hopper 12 in order to heat the mixture to about 350° C. before entering into the slot of the press.

The press is preferably operated by an adjustable driving gear, by which the number of revolutions of the disk can be regulated according to the properties of the material to be briquetted.

The material to be briquetted in the hopper 12, by the force of gravity, always tends to pass downwardly through the space defined by the edge of the sloping wall section 28 of the hopper and the edge of the hood 10 into the slot 27. The slot 27 is, however, only open for the passage of the briquetting material on the side away from the compression zone. This can be clearly seen in Fig. 1, where the slot 27 on the left-hand side is open for the passage of the briquetting material from the hopper 12 and closed on the right-hand side where the compression is being effected. In the open portion the material to be briquetted passes from the hopper 12 into the slot 27 between the disk 4 and the tongue 15. As can clearly be seen from Fig. 3, the tongue 15 is spaced from the disk on one side and close to the disk on the opposite side. As the tongue rotates with the hood and shaft and the disk eccentrically rotates in the opposite direction, the material to be briquetted may pass freely between the tongue and disk for compression between the disk and ring and the briquettes formed will be maintained separate from the material to be briquetted by the tongue on the opposite side of the disk.

As the scraper 16 and the shovel 17 are connected to the tongue 15, which, in turn, is connected to the hood 10 by means of the arm 14, as can be clearly seen in Fig. 6, as the shaft and hood rotate, the tongue, scraper and shovel will rotate therewith. The scraper 16 will thus free and break the briquettes, as shown in Fig. 3, and the shovel 17 will scrape the same into the discharge 18 from the space 21 in which they fall.

Instead of the springs 9 being positioned between one side of the part 5 of the shaft and the eccentric 21, a hydraulic cylinder and piston may be provided. Such an arrangement is shown in Fig. 4. The cylinder 25 is defined in the part 5, and a piston 24 is fitted in this cylinder. The fluid may be passed under pressure through 47 to press the piston 24 out of the cylinder 25 and thus resiliently urge the eccentric member radially outwardly in the eccentric direction.

With the apparatus according to the invention it is possible to produce briquettes from materials, which could not be briquetted in the usual types of presses. Very fine powdered coals can be briquetted without any binder and smokeless briquettes of a high quality can be made, saving the cost of binder. Coking-coals and mixtures of such with coke or ores can be briquetted, which opens a new possibility for producing metals from such heat resisting briquettes. The apparatus of the invention requires less power due to the very efficient method of compressing the material. The closed cycle of the power exerted in the press makes a relatively small device possible, which permits the application of a very high pressure. By the simple and closed design of the apparatus considerably less constructing material is required for it than for the known types of presses, and it can be manufactured and repaired without costly special tools, which are necessary for the known stamping presses or the roller-ring system.

What I claim is:

1. Apparatus for briquetting finely divided material comprising a fixed horizontal ring, a verti-

cal rotatable shaft coaxial with said ring, an eccentric member connected to said shaft, a horizontal disk positioned inside said ring and mounted for free rotation on said eccentric member, said ring and disc defining a circumferential briquetting channel therebetween for the formation of briquettes therein, means for feeding material to said channel, and means for removing briquettes from said channel.

2. Apparatus according to claim 1 in which said horizontal ring is fixed in a frame and in which said horizontal disc is supported at the bottom of said frame by a horizontal thrustbearing.

3. Apparatus according to claim 2 including a tongue connected for rotation with said shaft and positioned for partially closing said briquetting channel in a horizontal direction.

4. Apparatus according to claim 1 in which said means for removing briquettes from said briquetting channel include a scraper connected to said tongue and positioned for removing briquettes from said briquetting channel.

5. Apparatus according to claim 1 in which said eccentric member is connected to said shaft by spring means, said spring means being positioned for resiliently urging said eccentric member radially outwardly.

6. Apparatus for briquetting finely divided material comprising a horizontal ring fixed in a frame, a vertical rotatable shaft coaxial with said ring, an eccentric member connected to said shaft, a horizontal disc positioned inside said ring and mounted for free rotation on said eccentric member, said horizontal disc being supported at

the bottom of the frame by a horizontal thrustbearing, said ring and said disc defining a circumferential briquetting channel therebetween for the formation of briquettes therein, a central hopper positioned above said ring, at least one bar connected for rotation with said shaft and dimensioned and positioned in said central hopper for the mixing of materials therein and the uniform feeding thereof to said briquetting channel, and means for removing briquettes from said briquetting channel.

10 7. Apparatus according to claim 6 including at least one bar fixed on the inner wall of said central hopper.

15 8. Apparatus according to claim 6 including conduit means positioned for passing a hot gaseous medium into said central hopper.

20 9. Apparatus according to claim 1 in which said eccentric member is connected to said shaft by a hydraulic device positioned for resiliently urging said eccentric member radially outwardly.
